ATTORNEY.

UNITED STATES PATENT OFFICE

112,257

DESIGN FOR A SHOE OR SIMILAR ARTICLE

Kenneth B. Keyes, New York, N. Y.

Application October 22, 1938, Serial No. 80,614

Term of patent 3½ years

To all whom it may concern:

Be it known that I, Kenneth B. Keyes, a citizen of the United States of America, residing in the city of New York, county of New York, and State of New York, have invented a new, original, and ornamental Design for a Shoe or Similar Article, of which the following is a specification, reference being had to the accompanying drawing, forming part thereof.

Fig. 1 is a side view of a shoe or similar article showing my new design.

Fig. 2 is a perspective view thereof.

I claim:

The ornamental design for a shoe or similar article, substantially as shown.

KENNETH B. KEYES,
